UNITED STATES PATENT OFFICE.

VASIL MACKAY, OF BOSTON, MASSACHUSETTS.

FURNACE.

1,151,208.

Specification of Letters Patent. Patented Aug. 24, 1915.

Application filed August 21, 1913. Serial No. 785,858.

To all whom it may concern:

Be it known that I, VASIL MACKAY, a citizen of the United States, residing at Boston, in the county of Suffolk and State of Massachusetts, have invented an Improvement in Furnaces, of which the following is a specification.

This invention relates to certain improvements in furnaces which are designed to burn coal or coke, and more particularly to certain improvements in means for feeding the fuel to the grate and spreading it thereover.

Prior to my invention various automatic devices have been produced for feeding the fuel from the front to the rear of the furnace, but, so far as I am aware, no strictly automatic device has been produced which will maintain the fuel at a predetermined depth, under all conditions, and during the various fluctuations of the demands of the boiler which ordinarily occurs.

The object of my invention is to provide automatic means for supplying fuel to the furnace grate, distributing it thereover to a uniform depth and maintaining it at this depth under all conditions, so that all variations in rapidity of consumption will be compensated for.

A further object of my invention is to provide means for breaking up and dumping the clinkers at the rear end of the grate, so that the use of hand implements for that purpose is made unnecessary and the employment of a long grate surface is made practical.

I accomplish these objects by the means shown in the accompanying drawing, in which,

Figure 1 is a side elevation, partly in section, showing an ordinary steam boiler provided with a grate and fuel feeding devices made according to my invention. Fig. 2 is a plan view of the furnace grate. Fig. 3 is a front elevation, showing the operating mechanism. Fig. 4 is a detail front view of the grate operating mechanism. Figs. 5 and 6 are detail views partly in section of the grate bars, and their operating means, Fig. 7 is a detail front view of one of the

grate-bars. Fig. 8 is an enlarged sectional view taken at the line $y-y$, of Fig. 6.

In Fig. 1 of the drawings I have indicated, in a general way, a boiler of a well-known type, provided with my invention, 1 indicating the front wall of the furnace, and 2 the boiler supported above the furnace in the usual manner.

According to my invention I provide the furnace with two sets of grate-bars 3 and 4, 60 the bars 3 being arranged alternately with the bars 4, and all of said bars being arranged in the position usually occupied by the grate in furnaces of this character, and, while two separate series of grate-bars are 65 shown in Fig. 2, it will be obvious that, so far as my invention is concerned, it is immaterial how many series are employed. The grate-bars are arranged to extend transversely of the furnace, or parallel to the 70 front wall thereof, and normally present an approximately horizontal surface, as is customary, said bars being identical in form, the separation into sets being made for convenience in description. Said grate-bars 75 are each approximately of sector shape in cross-section and have a segmental shaped front side, the upper and lower sides thereof extending convergently from the edges of said front side and terminating in a 80 rounded, or shaft-like rear portion which is extended beyond the ends of the bar to provide end trunnions 3' or 4', as shown in Figs. 2 and 6, the whole being cast integrally. The upper surface of each grate-bar 85 is arranged to extend tangentially from said rounded rear portion, and the segmental shaped front side is curved on an arc having the axial line of said trunnions as a center, so that said upper surface extends nearly 90 perpendicularly or radially to said front surface. Said trunnions rest in longitudinally extending supports 5, which are recessed to receive the same and said grate-bars are held so that the rounded rear edge 95 portion of each bar is arranged closely adjacent, but out of contact with, the front side of the next adjacent bar, the space therebetween preferably being only wide enough to permit clearance, when the bars are swung 100

on their trunnions, as hereinafter described. With this arrangement, when either bar is swung on its trunnions, this space between the front side of one bar and the rear side 5 of the next adjacent bar will not be appreciably increased : diminished, and, as the upper surface of each grate extends tangentially to the surface of its rounded rear side portion, which is continuous with the surface 10 of the trunnion, when the grate is swung on its trunnions from a horizontal position, upwardly and away from the front of the furnace, substantially its entire upper surface will be raised. Each grate-bar is 15 also provided with transversely extending draft slots *a* which extend vertically therethrough from the upper to the lower side, and also with draft slots *b* of similar size in the front face thereof which lead to the 20 openings *a* from the front side of the bar, so that passages or draft-slots are provided from the lower side of the bar both to the upper and front sides thereof. To provide operating means for said grate-bars, arms 6 25 are radially mounted in the rounded rear portions of grate bars 3 and arms 6' in the corresponding portion of the grate bars 4, which are alternated with grate bars 3, in such positions that, when the upper surface 30 of any grate bar is in horizontal position, its corresponding arm will be then depended therefrom nearly vertically.

A rod 7 is connected to the arms 6, and a rod 8 is connected to the other arms 6', so 35 that, when the rod 7 is drawn forwardly, or moved longitudinally toward the front of the furnace, all of the grate-bars 3 will be swung upwardly on their trunnions and, when the rod 8 is drawn forwardly, all of the 40 grate-bars 4 will likewise be swung upwardly. With this arrangement one set of alternate grate-bars only may be swung upwardly at one time, by moving one rod, and then the others may be likewise moved, or 45 all of them may be thus moved together by moving both rods together, or by connecting all of the arms to one rod, and it will be obvious that the rods 7 and 8 may be operated mechanically or manually in any relative time desired. However, as I secure results by operating them alternately which I cannot secure by operating them together, I 50 preferably provide suitable mechanical means for this purpose. Such mechanical means preferably comprises a main shaft 9 which may be constantly driven from any suitable source, and an operating shaft 10 which is mounted adjacently, and on which a gear 10' is provided which is arranged in 55 mesh with a gear 9' on shaft 9, said shafts being preferably arranged in a chamber formed in the front wall of the furnace, as shown. A pair of collars 12, 12' having fingers 13, 13', respectively, thereon, are ad-

justably mounted on the shaft 10, being secured thereto by a set-screw *x*, or other suitable means, as shown in Fig. 8, said fingers being arranged diametrically opposite in position to engage laterally projecting lugs 14 and 14' formed on collars or clips mounted 60 for longitudinal adjustment on the rods 7 and 8 respectively, so that, for example, when the shaft 10 is rotated in the direction of the arrow Fig. 5, the finger 13 will engage the lug 14 and the bar 7 will be drawn 65 forwardly, causing arms 6 to be swung in the same direction and the grates 4 to be swung upwardly, and rearwardly, as shown in Fig. 1. After the rod 7 has been drawn forward to a certain extent, the finger 13 will become disengaged from said lug, so 70 that the grate-bars 3 will be free to swing down by the action of their own weight, and by that of the fuel thereon, to their normal positions. This operation will take place 75 during one half a revolution of shaft 10 and during the other half of the revolution the other set of bars 4 will be operated in like manner as will be obvious. Any suitable means to limit the downward movement 80 of the bars at the horizontal position may be provided on said rods 7, 8, which limits its rearward movement, as by providing stoppins, as 15, thereon, which engage the rear wall of the chamber containing said shafts 85 9 and 10. The extent to which the bars 3 and 4 may be swung upward may be varied 90 by adjusting the lugs 14, 14' longitudinally of the rods on which they are mounted. A fuel hopper 17 is arranged on the front side 100 of the furnace and leads to a chamber 18 in the front wall thereof, and a fuel feeder 19 is arranged in the bottom of said chamber, said device being imperforate, but of similar shape to said grate-bars, and being similarly pivoted at its ends on trunnions 20, the rear side of said feeder being arranged directly in front of, and at a short distance from the front side of the first grate-bar 3. Said feeder is likewise provided with an 110 arm 21, which depends therefrom and is arranged to be engaged by one or more lugs 22, which project laterally from collar 12 and may be diametrically, or otherwise disposed thereon, so that, as the shaft 10 is rotated said lugs will engage said arm 21 and swing it forwardly from the dotted line position of Fig. 6 to the full line position thereof, thus causing the front portion of 115 the feeder to be swung upwardly in a manner similar to that in which the grate-bars are operated, as previously described. The shaft 10 serves as a stop to limit the rearward swinging movement of arm 21.

A clinker-breaking and dumping grate-bar 23 is pivotally mounted on trunnions 24 between the rear grate bar 4 and the rear wall of the furnace, said trunnions being lo-

cated at the front side thereof adjacent the trunnions of said grate-bar 4, as shown in Fig. 1. An arm 25 is connected thereto, and extends radially with relation to the trunnions, and said arm is connected by a rod 26 to a hand lever 27 arranged in the front of the furnace, so that, by drawing forwardly on said lever 27, said bar 23 may be swung upwardly and forwardly on its trunnions. The furnace is formed to provide a fuel-retaining abutment 28 directly in the rear of the grate-bar 23.

The operation of my device is as follows: Fuel having been introduced into the hopper 17, it falls into the chamber 18 upon the feeder 19, and, as said feeder is swung up by the action of shaft 10, it will throw rearwardly the fuel on the next adjacent grate-bar, while the latter is in a horizontal, or nearly horizontal position, and then the fuel, which is thus discharged on the first grate-bar, will be discharged on the one next succeeding and in like manner the fuel will be delivered from one bar to the next until it reaches the rear end of the furnace, where it will be delivered onto the dumping grate-bar 23, and then will be piled thereon against the abutment 28. The fuel is thus fed over the entire grate-surface, and is consumed as it is fed to the rear, and, ordinarily, all impurities will be delivered on the rear bar 23, where they will be dumped when necessary.

By the above described operation a uniform distribution of the fuel over the entire grate-surface is secured, and the fuel is maintained, practically, at a uniform depth throughout said surface, said depth depending on the width of the grate-bars and their range of movement from the horizontal. That is, under certain given conditions it is impossible for a grate to convey the fuel forward when the depth of the fuel in front of it has reached a certain point, for the reason that when the bar is raised, it will be prevented from delivering the fuel to the next bar by the fuel thereon, so that the fuel will remain thereon and be returned to its previous position when the bar is lowered. One grate-bar will thus feed along the fuel to the next when the depth of the bed of fuel is less than the maximum point, but will not feed it along when its depth has reached this point. In case the fuel is consumed faster at one side of the furnace than at the other, the fuel will be fed correspondingly faster at the one side than at the other. In the ordinary operation of the furnace, therefore, the grate-bars will feed the fuel forwardly until it begins to accumulate on the back-bar 23 and becomes piled against the rear wall 28. This operation will continue until the fuel on the back-bar 23 reaches such a depth that it prevents the rear feeding bar 4 from feeding more fuel

back onto said bar 23 and this bar 4 then becomes filled to the same depth, and then in like manner the succeeding bars from rear to front become filled to a like depth successively, and, when the front bar 3 becomes filled, the fuel thereon will prevent the feeder 19 from delivering more fuel from the fuel chamber onto said front bar. The grate will thus be covered to the desired depth from rear to front and the fuel will only be fed forward by the grate-bars when its level is reduced by being consumed, or when the ash and clinkers are dumped from the rear bar 23, so that the feeder 19 may again deliver fuel to the bars. As the feeder and grate-bars will be operated frequently enough to supply fuel as fast as, or faster than it is consumed under all conditions, it not only follows that the fuel will automatically be maintained at the desired level, but by the combination of means which causes the fuel to be held at this level at the rear, and the feeding means to the alternately operating grates which will only feed forward fuel to the grate when the fuel level on the front bar is below normal, the possibility that too much fuel will be fed to the furnace at any time, as for instance, in case the consumption should be much below normal, is avoided. Ordinarily the tendency is for the bed of fuel to decrease in depth more rapidly in the inner or rear part of the furnace than in the front, for the reason that the fuel will have become much more nearly reduced to ashes when it has reached said inner portion, so that, ordinarily, there will always be some forward feeding of the fuel, but this will be only according to requirements.

The alternate operation of the grate-bars not only acts to feed back the fuel, as described, but also acts to break up the crust which usually forms on the surface of the fuel, when soft coal is used, thus giving a free draft therethrough and making the use of a slice-bar unnecessary. This latter result may be secured by operating the connecting rods independently or simultaneously.

As the clinkers will be delivered on the grate-bar 23, they may be broken up by swinging said bar upwardly and forwardly at intervals. The clinkers, when broken up, may also be dumped into the ash-pit by drawing forwardly the rod 26.

While the downward swinging movement of grate-bars 3 and 4 is normally limited at the horizontal position, if it is desired to dump the fuel on the grate into the ash-pit, it is merely necessary to remove the stop-pins 15 from the rods 7 and 8, so that said bars may be pushed rearwardly and the grate-bars swung downwardly, permitting the fuel to slide from them.

By employing the particular form of grate-bars above described, an increased grate surface, through which the air may pass, is provided, when the bars are in 5 raised, or partly raised position, by the provision of the draft slots therethrough, as the air will pass from the under side of the grate both through the top and front thereof. This action, together with the constant 10 breaking up of the fuel, which occurs by the lifting and lowering of the bars, greatly assists in increasing the draft.

From the foregoing description it will be 15 apparent that I provide a grate device which acts both as a mechanical stoker and as a mechanically operated means to keep the draft passages of the grate open to an extent sufficient to provide the necessary draft. It will further be observed that, with 20 the above described arrangement the fuel may be fed any distance, *i. e.*, a furnace of any desired length may be employed, as the fuel may be fed from its front to its rear end and maintained at a uniform depth 25 throughout its entire length.

I claim:—

1. In a furnace, a series of horizontally disposed, transversely extending grate-bars adjacently arranged in parallelism, each pivotally supported to swing about a longitudinal axis at its rear side, fuel-delivery means arranged to deliver fuel onto the first grate-bar of said series and operative only when the depth of the fuel on said bar is below the normal level to be maintained, and 30 inoperative when said level is reached, automatically operating means to swing one set of alternate bars upwardly and then the other, to feed the fuel from said front bar toward the rear, and fuel retaining means adjacent the rear bar of said series for preventing rearward feeding of the fuel and to cause it to accumulate to the normal level 35 from rear to front, whereby the fuel may thereafter be automatically maintained at 40 said normal level.

2. In a furnace, having a fuel-chamber at its front side, a series of horizontally disposed, transversely extending grate-bars adjacently arranged in parallelism, each pivotally supported to swing about a longitudinal axis at its rear side, the front bar of 45 said series being arranged adjacent said chamber to receive fuel therefrom, a non-positively operating fuel delivering means in said chamber adapted and arranged to deliver fuel from said chamber on the said front bar, and operative only when the depth of the fuel on the latter is below a predetermined level, operating means to 50 actuate said delivery means and to swing one of said alternate bars upwardly and then the other to feed the fuel toward the rear, and fuel retaining means directly in the rear of

said bars to cause the fuel to accumulate to 65 a predetermined depth from rear to front and prevent feeding action of said delivery means except when said fuel depth is reduced below said level.

3. In a furnace, having a fuel-chamber in 70 its front side, a series of horizontally disposed, transversely extending grate-bars adjacently arranged in parallelism, each pivotally supported to swing about a longitudinal axis at its rear side, the front bar of 75 said series being arranged adjacent said chamber, a fuel-retaining wall at the rear of said bars extending upwardly from the level of the grate to an extent sufficient to hold the fuel at a predetermined level, a 80 non-positively operating fuel feeding means adapted and arranged to deliver the fuel from said chamber to the front grate-bar, and operative only when the fuel on said bar is below said predetermined level, and 85 operating means to actuate said feeding means and to swing one set of alternate bars upwardly and then the other, to feed the fuel from said chamber toward said retaining wall and to maintain a substantially constant fuel level.

4. In a furnace, having a fuel-chamber at its front side, a series of horizontally disposed, transversely extending grate-bars adjacently arranged in parallelism, each pivotally supported to swing about a longitudinal axis at its rear side, the front bar of 95 said series being arranged adjacent said chamber, a feeding device shaped similarly to said grate-bars and pivotally supported 100 in said chamber closely adjacent said front grate-bar, and in parallelism therewith to swing about an axis at its rear side, operating means to swing said feeding device upwardly to discharge fuel from said chamber onto said front grate-bar when it is lowered, and to swing one set of alternate bars upwardly and then the other to feed the fuel rearwardly over said bars, said feeding device being operative to feed the fuel 110 only when the depth thereof is below the normal level, and fuel-retaining means arranged directly in the rear of said bars for causing the fuel to accumulate to a depth beyond which said bars are inoperative to 115 feed the fuel, whereby, as the fuel accumulates to said depth from rear to front, said bars and said feeding device become inoperative to feed the fuel.

5. In a furnace, a series of horizontally 120 disposed, transversely extending grate-bars adjacently arranged in parallelism, each pivotally supported to swing about a longitudinal axis at its rear side, fuel-delivery means arranged to deliver fuel onto the 125 first grate-bar of said series and operative only when the depth of the fuel on said bar is below the normal level to be main-

tained, and inoperative when said level is reached, operating means to swing one set of alternate bars upwardly and then the other, to feed the fuel from said front bar toward the rear, and fuel retaining means adjacent the rear bar of said series for preventing rearward feeding of the fuel and to cause it to accumulate to the normal level from rear to front, whereby the fuel may

be maintained at a predetermined level, 10. without raising it above said level.

In testimony whereof, I have signed my name to this specification, in the presence of two subscribing witnesses.

VASIL MacKAY.
